UNITED STATES PATENT OFFICE.

HARRY MUSGILLER, OF BALTIMORE, MARYLAND, ASSIGNOR TO JOSEPH W. WEISS,
OF BALTIMORE, MARYLAND.

HAT STAY.

Application filed July 10, 1924. Serial No. 725,272.

To all whom it may concern:

Be it known that I, HARRY MUSGILLER, a citizen of the United States of America, residing in the city of Baltimore, State of Maryland, have invented certain new and useful Improvements in Hat Stays, of which the following is a specification.

The invention relates to a hat package or more particularly to a stay consisting of spacing and positioning means for packing straw and other stiff hats in a box, the present device being in the nature of an improvement on that described in the patent to Joseph W. Weiss, No. 1,109,722, of September 8th, 1914.

The object of the invention is, as stated in the previous patent, to reduce the cost of packing straw and stiff hats by reducing the cost of shipping the empty boxes and stays, and hence reducing their cost at the factory.

The previous patent relates to a collapsible box and collapsible hat stay. The patented package consisted of a hexagonal or similar box elongated in the direction of the axis, each box being ordinarily of a size and shape to receive a half dozen hats with the brims and crowns parallel and what may be termed the axis of the hats in alignment. The stays or spacing and positioning means consisted of a closed circular band intended to enclose the crown of the hat, and a flat plate of heavy paper or pasteboard fitting the cross-section of the box and having an aperture of the shape and of a little larger size than the crown. The ring or band which was permanently fastened at the ends to form a ring or loop and of a short cylindrical form, was placed inside the aperture and fastened to it by tongues formed on the plate which were inserted in slots in the band.

The plates served to position the hats laterally, i. e., to keep the edges of the brims from rubbing against the sides of the box, keeping them well out of contact, and the bands which encircled the crowns of the hats served to space them in the direction of the height of the crown or what may be termed the axis of the hat. The tongues referred to were formed on the plates near the aperture and were passed through slots in the paper band to hold it in position. The

patented device was found objectionable on account of the rubbing of the ends of the tongues against the hat, in some instances causing some slight injury to the hat bands and the neighboring surfaces of the hat. Also the cylindrical member or paper band which encircled the crown and acted as a spacing member, was a continuous ring-shaped band which in packing folded flat. The resulting creases in the ring or cylindrical band were found undesirable as they made it difficult to assemble the stay and insert the hats and the tongues did not properly retain their position in the band or properly perform the function of holding the parts.

The present invention relates particularly to a hat stay or positioning and spacing means, and overcomes and eliminates the difficulties recited, providing a device which is improved in various ways. It is of interest to note that other stays have been made which are quite satisfactory in serving the function of spacing and positioning the hats in the package, but these stays are permanently fastened and not of the knock-down type, incurring an additional expense in shipping which adds materially to the cost of packing the hats.

The present device has the additional advantage that it not only provides a satisfactory spacing and positioning stay which does not injure the hats, but one which may to advantage be completely knocked down and shipped flat, so that the boxes and stays complete may be packed with entire economy as to space, thereby greatly reducing the cost of shipping.

In the accompanying drawing I have shown a hat package including a hat stay embodying the improvement of my invention in the preferred form, illustrating two slightly different forms of stay.

In the drawing,—

Figure 1 is a vertical central section illustrating a hat package including a box and a hat stay with the hats packed therein in accordance with my invention.

Figure 2 is a perspective view illustrating one of my hat stays assembled and ready for use, the same being of the type used to support two hats or a single hat with an unusually high crown.

Figure 3 is a fragmentary vertical central section illustrating the construction of the hat stay, Figure 2, and showing the same with the hats therein ready for packing in a box.

Figure 4 is an external elevation of a hat and hat stay assembled ready for placing in the box, the type illustrated in this view being intended to hold a single hat.

Figures 5 and 6 illustrate the hat stay disassembled, Figure 5 showing a plan of the brim spacing member and Figure 6 a plan of the crown spacing member, the latter being disconnected at the ends and extended, and being of a width which corresponds to a stay, accommodating a single hat.

Figure 7 is a perspective view of the hat package complete, showing the same slightly below the observer, and with the cover removed and spaced upwardly from the box for purposes of illustration.

Referring to the drawings by numerals, each of which is used to indicate the same or similar parts in the different Figures, the package as illustrated in Figure 1, consists of a box which may be cylindrical or polygonal, the box illustrated in Figure 7 being of hexagonal cross-section. The box 1 referred to is of a cross-section corresponding roughly in shape to the outline of the brim of the hats to be packed and slightly larger, so that the brims may be spaced from the sides of the box to avoid injury. The box 1 has suitable end walls or covers 2 at each end, the ends being formed with a flange 3 to fit and enclose the side walls 4 of the box. These may be secured in any suitable manner as by gluing or by means of paper strips or stickers or the box may be wrapped with cord, any suitable and well-known fastening being available for this purpose.

As an important feature of this package is the facility with which the packing members, i. e., the box and stay, may be knocked down and packed flat and set up to enclose and protect the hats for shipment, saving a large proportion of the expense of shipping the boxes and stays to the factory, the box itself is necessarily and obviously of the knock-down variety, such boxes being disclosed in the application above cited and at this time well known to the trade. The end walls or covers 2 as shipped are separate from the side walls 4, which are unfolded or collapsed and packed flat.

The important feature of the present invention is the hat stay which has been improved as to its details of construction, providing a practical knock-down hat stay which can be packed absolutely flat without loss of efficiency and can be assembled quickly, giving a satisfactory stay which does not injure the hat or trimming, avoiding the possible difficulties incident to the

previous structure. The stay is illustrated assembled in Figures 2, 3 and 4, and knocked down in Figures 5 and 6.

The stay consists of a brim spacing and protecting member 6 in the form of a flat plate or sheet of pasteboard or cardboard, as it is known, having a central opening 7 for the crown and slots 8 at the sides. The crown spacer 9 consists of a flat band or strip of cardboard or pasteboard having temporary or releasable fastening means 10, 11 at the ends, and tongues or tabs 12 cut from the paper which forms the band, and spaced apart by a suitable portion of the length of the band to cause them to correspond and enter the slots 8 in the brim spacer when the structure is assembled, as hereinafter described.

The fastening means 10 and 11 at the ends consists of transverse slots 10 extending transversely to the length of the band, and tabs or tongues 11 extending in the direction of the length of the band and adapted to enter the slots 10. As shown, the tongues 11 are turned toward the longitudinal centre of the band. The tongues or tabs 12 are preferably turned at right angles to the length of the band, the important point being that they are formed on the band and turned outward in assembling, so they do not contact with the hats.

As already stated, the box and stay are packed flat and so shipped to the hat factory. To pack the hats, the boxes and stays are first assembled. The manner of assembling the box is explained in previous patents and is well understood, the side wall member 4 being preferably tubular formed to fit the end covers, one of the covers is placed over a corresponding end and the parts are secured in any suitable manner as by means of slips of paper coated with mucilage or by gluing, stitching or stapling, or in some instances all of these fastenings may be dispensed with.

To assemble the stay the band 9 is bent in the direction of its length, forming a ring or cylinder, as shown in Figure 12, which operation of bending may be performed inside the opening 7 in the brim spacer 6, or it may be performed outside, and the crown spacer inserted in the opening after it has been bent into a ring or cylinder, as shown in Figure 2. The ends are then fastened together by means of the slots 10 and the tabs 11, the latter tabs being turned in the form illustrated, toward the centre of the band, though the exact manner of fastening the ends of the band is immaterial, the important point being that the band is so constructed that it may be packed flat without folding. When this band is connected at the ends so that it must be folded flat at the ends, and therefore creased at two points in its length, it cannot be easily and conveniently

iently assembled, and when assembled, the parts do not maintain the desired relation, making it difficult to insert the crowns of the hats within the bands.

When the ends of the band 9 have been closed as described, the tabs 12, 12 are inserted in the slots 8, 8, completing the assembling of the hat stay. It is important to note at this point that the tabs or tongues 12 are turned outwardly in the assembled structure, whereby the chance of injury to the hats by scraping of the hats with the ends of the tabs or tongues 12 is avoided. Thus one of the important difficulties of the prior patented device is overcome, for the scraping of the crowns of the hats packed in the old form of hat stay by the ends of the tongues, is one of the important causes which contributed to its lack of success, the other being the difficulty incident to using a creased crown spacer. When the stays are thus assembled, the hats are inserted therein after the manner illustrated in Figures 1 and 3, the crowns being placed within the crown spacing bands 9 and the brims 16 being parallel to the brim spacer.

The stays may be made in either double or single form or both. Usually a stay having a single crown spacer, as illustrated in Figure 4, of little more than the height of a single crown, is used at each end of the box, the double crown spacers 9 being used for the four hats between the top and bottom. The hats are ordinarily packed in half dozen lots. It is easily apparent that the hats thus placed in the spacers may be dropped into the boxes either 1 or 2 at a time, depending upon whether the double or single stays are used. It will also be apparent from examination of Figure 1 that the crown spacers 9 serve to keep the crowns of the hats out of contact with each other and out of contact with the ends of the box, protecting and spacing them, and that the brim spacers 7 position the hats laterally and keep the edges of the brims out of contact with the side walls of the box.

The important features of the invention reside in the structure whereby the fastening members 12 which connect the crown spacers to the brim spacers are turned outwardly, avoiding injury to the hats, and the crown spacer bands 9 are so constructed that they may be packed flat without folding,

having temporary or releasable fastenings 55 10, 11 at the ends.

I have thus described specifically and in detail a hat stay embodying my invention in the preferred form in order that the nature and operation of the same may be clearly 60 understood; however, the specific terms herein are used descriptively rather than in a limiting sense, the scope of the invention being defined in the claims.

What I claim and desire to secure by Letters Patent is:

1. The combination with a hat box of a hat stay consisting of a brim spacer in the form of a flat plate fitting the cross-section of the box and larger than the brim of the 70 hat to be packed, and having an aperture to admit the crown of the hat, and slots at the sides of the aperture, and a crown spacer in the form of a band which is flexible in a longitudinal direction and having separable 75 fastening means to connect its ends, so that it may be packed flat and assembled by connecting the ends forming a ring which fits inside the aperture in the brim spacer and encloses the crown, the crown spacer having 80 tongues to fit slots in the brim spacer, the tongues being turned outwardly away from the crowns of the hats, the crown spacer being of a width greater than the height of the crowns of the hats to be 85 packed.

2. A hat stay consisting of a brim spacer in the form of a flat plate larger than the brim and having an aperture to admit the crown, and a crown spacer in the form of a band which is flexible in a longitudinal direction and relatively stiff transversely, the band having releasable fastening means at the ends, the length between the fastenings being equal to the circumference of the 90 aperture in the brim spacer, the crown spacer having a width greater than the height of the crowns of the hats to be placed in the stay and having tongues and means for fastening same to the brim spacer so 95 that they are turned outwardly away from the crowns of the hats.

Signed by me at Baltimore, Maryland, this 8th day of July, 1924.

HARRY MUSGILLER.
